UNITED STATES PATENT OFFICE.

NEWTON W. JONES, OF FRANKFORT, INDIANA.

STOCK-RACK.

1,150,203.

Specification of Letters Patent.

Patented Aug. 17, 1915.

Application filed October 3, 1914. Serial No. 864,885.

To all whom it may concern:

Be it known that I, NEWTON W. JONES, a citizen of the United States, residing at Frankfort, in the county of Clinton and 5 State of Indiana, have invented certain new and useful Improvements in Stock-Racks, of which the following is a specification, reference being had to the accompanying drawings.

10 This invention relates to an improved stock rack and has for its primary object to provide a simply constructed serviceable device of this character which is primarily designed for use in slaughter houses and to 15 provide means for conveniently suspending the stock after it is slaughtered.

The invention has for a more particular object to provide improved means for mounting an annular track upon a post or 20 supporting standard, said track being designed to receive the gambrels or like elements from which the stock is suspended.

The invention has for a further very important object to provide an apparatus of 25 the above character which is so constructed that the parts thereof may be very compactly assembled in a knocked down condition for convenience in shipment or transportation.

30 With the above and other objects in view, my invention consists in the novel features of construction, combination and arrangement of parts to be hereinafter more fully described, claimed, and illustrated in the accompanying drawings, in which,

Figure 1 is a side elevation of my improved stock rack, certain parts being broken away; Fig. 2 is a top plan view; Fig. 3 is a section taken on the line 3—3 of Fig. 2; and 40 Fig. 4 is a top plan view showing the track and its supporting parts removed from the standard.

Referring in detail to the drawings, 5 designates a perpendicular post or standard the 45 lower end of which is anchored in a concrete base or foundation 6 which extends below the ground surface. A pipe union or coupling member indicated at 7 is adapted to be removably threaded in the upper end of the 50 post or standard 5 which is formed from a pipe of suitable length and the flange of this coupling member is provided with a series of openings for a purpose to be later referred to. At a point in spaced relation 55 to the member 7, a ring or annulus 8 is secured upon the standard.

An annular track 9 of any desired diameter is connected to the annulus 8 by means of a plurality of radially extending rods 10. The inner ends of these rods are riveted, 60 bolted, or otherwise suitably fixed to said annulus and adjacent to their outer ends are upwardly offset as at 11 and suitably fixed at their extremities in the track 9.

12 designates a plurality of obliquely inclined truss rods provided with eyes 13 upon one of their ends to receive fastening bolts 14 which are adapted to be threaded into the cap member 7. The other or outer ends of the truss rods 12 are provided with rings 70 or loops 15 engaged upon the respective rods 10 and with the vertical shoulders formed by the offsets 11 therein.

Upon the upper end of the standard 5, one end of a crane arm 16 is pivotally mounted. 75 This arm projects outwardly and downwardly slightly beyond the annular track 9 and has a sheave or pulley 17 suitably mounted in its outer end. A brace rod 18 is pivotally connected at its outer end to the 80 arm 16 and the inner end of said rod is disposed through an opening in the post or standard 5 indicated at 19. Nuts 20 are threaded upon said rod on opposite sides of the post to securely hold the same in its adjusted position. It will be readily understood that by adjusting the rod 18 inwardly or outwardly, the outer end of the crane arm 16 may be raised or lowered, as desired.

A horizontally disposed yoke bar 21 embraces the standard 5 and has its intermediate portion securely fixed thereto by means of the bolt 22. In the parallel arms of this yoke which project beyond one side of the standard, the opposite ends of a roller or 95 drum 23 are suitably journaled. The ends of this drum are provided with rectangular studs or extensions to receive suitable cranks 24. Upon one end of the drum or roller a ratchet disk 25 is fixed, the teeth of which 100 are adapted to be engaged by a gravity pawl 26 fulcrumed as at 27 upon one arm of the yoke 21. The drum is also provided with a transverse opening to receive a pin indicated at 28 which is attached to one end of 105 a rope 29. This rope extends over the sheave or pulley 17 mounted upon the arm 16 and is equipped at its other end with a hook or like attaching means 30 whereby the rope may be readily connected to the object 110 to be elevated.

A transversely disposed rod 31 is also

fixed in the standard 5 and is provided upon its ends with the rings or eyes 32 to which a hitching line or rein may be conveniently attached.

- 5 33 designates the wheel or roller mounted upon the annular track 9 to the axis of which a depending hook 34 is connected. To this hook a gambrel 35 of any approved construction may be removably attached.
- 10 It will be understood that any desired number of these traveling rollers 33 may be mounted upon the track.

In the use of my improved apparatus, the same is erected adjacent to the butchering 15 platform, and after the feet of the animal have been properly tied in the usual manner, the hook 30 on the end of the rope 29 is connected to a head loop or sling which has been applied to the animal. The drum or 20 roller 23 is then rotated by means of the cranks 24 and the animal elevated in convenient position to be killed and butchered. In a similar manner, wagon bodies or hay racks may be readily elevated from the running gear of the vehicle.

In the shipment of the device or when it is no longer desired for use, the truss rods 12 may be disconnected from the cap plate 14 and after the removal of said plate from 30 the upper end of the post, the ring 8 may also be slipped upwardly over the end of the post and removed together with the annular track 9. The truss rods 10 are then folded inwardly and downwardly upon the annulus 8 in the manner illustrated in Fig. 4. It will therefore be apparent that a large 35 number of the devices may be compactly arranged so as to occupy but a minimum of space.

40 From the foregoing description, taken in connection with the accompanying drawings, the construction, manner of operation, and several advantages of my invention will be clearly and fully understood. The apparatus may be easily and quickly set up 45 in condition for use or the parts thereof disassembled. It will also be apparent that the invention is extremely strong and durable in its construction and in view of its 50 comparative simplicity, it may be produced at small manufacturing cost.

While I have above referred to the present preferred construction and arrangement of the several elements, it will be understood

that the invention is susceptible of considerable modification therein, and I therefore reserve the privilege of resorting to all such legitimate changes as may be fairly embodied within the spirit and scope of the invention as claimed.

Having thus described my invention, what I desire to claim and secure by Letters Patent is:—

1. In an apparatus of the character described, the combination of a standard, an annular track, an annulus fixed to the standard, radially disposed rods rigidly connected to the track and to said annulus, a cap plate removably mounted upon the upper end of the standard, obliquely disposed rods 65 removably attached at one of their ends to said cap plate and having their other ends slidably engaged upon said radial rods, each of the radial rods being provided with a stop for engagement by the sliding end of 70 the truss rod whereby the truss rods are retained in an obliquely inclined bracing position between the track and said cap, said truss rods being foldable upon the radial rods to lie in a plane substantially parallel 75 with relation thereto.

2. In an apparatus of the character described, the combination of a standard, an annular track, an annulus removably secured upon the standard, radially disposed 80 rods rigidly fixed at their ends to said annulus and to the track, a cap plate removably mounted upon the upper end of the standard, each of said radial rods being provided adjacent to its outer end with an angular offset, and truss rods detachably connected at one of their ends to the cap plate 85 and having eyes upon their other ends slidably engaged upon the respective radial rods, said eyes being adapted to be engaged 90 with the offset portions of the radial rods, whereby the truss rods are retained in obliquely inclined bracing positions between the track and said cap plate, said truss rods being foldable to lie in a plane substantially 95 parallel with relation to the radial rods.

In testimony whereof I hereunto affix my signature in the presence of two witnesses.

NEWTON W. JONES.
